UNITED STATES PATENT OFFICE.

GEORGE BROWNING AND PATRICK J. BOHAN, OF SAN DIEGO, CALIFORNIA.

WRENCH.

Application filed February 16, 1925. Serial No. 9,460.

Our invention relates to wrenches, particularly socket wrenches, and the objects of our invention are: first, to provide a wrench having a means in connection with the wrench member thereof whereby the nut, bolt head or other member engaged by the wrench member may be successively rotated portions of a turn without removing said wrench member from said nut, bolt head or other member; second, to provide a wrench of this class having a handle member longitudinally shiftable at the one end of the wrench member thereof; third, to provide a wrench of this class having a handle member adapted to be longitudinally shifted relatively to the one end of the wrench member thereof and adapted also to be shifted to one side and folded to the side of the wrench member; fourth, to provide a wrench having a wrench member provided with diametrically opposed notches at its one end adapted to receive the one end of the handle portion of the handle means shiftably mounted at said end of the wrench member; fifth, to provide a wrench of this class having a handle member longitudinally shiftably mounted at the one end of a wrench member and provided at the portion of said handle member mounted in said wrench member with a retaining means pivotally connected thereto, whereby said handle member is retained in association with said wrench member for rotating the same, or whereby said handle member may be folded to one side of the wrench member; sixth, to provide as a whole a novelly constructed wrench, and seventh, to provide a wrench of the character mentioned which is very simple and economical of construction, durable, efficient, compact when folded, and which will not readily deteriorate or get out of order.

With these and other objects in view, as will appear hereinafter, our invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is an end view of our wrench structure, with the handle member thereof in operative relation with the wrench member; Fig. 2 is a side elevational view there-

of, showing certain parts and portions broken away and in section to facilitate the illustration and showing fragmentarily by dotted lines the handle and other members withdrawn from the one end of the wrench member; Fig. 3 is another side elevational view of our wrench with the handle member thereof folded to the one side of the wrench member, and Fig. 4 is an end view of the wrench when folded as shown in Fig. 3.

Like characters of reference refer to similar parts and portions throughout the several views of the drawings.

The wrench member 1, head member 2, handle member 3, retaining member 4, and the pin 5, constitute the principal parts and portions of our wrench structure in its preferred embodiment as a socket wrench.

The wrench member 1 is preferably tubular and provided at its one end with a wrench portion 1^a in the form of a socket adapted to receive a nut, bolt head, spark plug, and the like, the structure illustrated in the drawings being particularly adapted for spark plugs. At the opposite end of the tubular wrench member 1 is provided a plurality of relatively deep recesses or notches 1^b which are diametrically opposed to each other and adapted, when the wrench is in operation, to receive the one end 3^a of the handle member 3, the extended portions 1^c at the last mentioned end of the member 1 being engageable by the handle member 3 when desiring to rotate the member 1. Within and at the one end of the tubular member 1 provided with the notches and slightly spaced inwardly from the lower end of said notches is a head member 2 provided with a central hole 2^a into which is adapted to be inserted a portion 3^b extending at right angles from the main portion of the handle member 3 between the portions thereof positioned between oppositely disposed slots of the member 1. At the end of the portion 3^b is pivotally connected, by means of a pin 5, the lug portion 4^b of the handle retaining member 4, the lug being provided at the end opposite its pivotal connection with the portion 3^b with an enlarged member or disc 4^a which is adapted to engage the inner side of the head member 2 when the handle member 3 is withdrawn.

It will be here noted that the head member 2 may be in the form of lugs punched inwardly from the wall of the member 1, if desired.

When desiring to change the position of the handle member 3 relatively to the wrench member 1, the handle member is withdrawn to the dotted line position and again shifted inwardly into other notches adjacent those previously occupied, the retaining member 4 preventing the complete withdrawal of the handle member from the wrench member 1. Thus, it will be seen that the nut, bolt head, spark plug, or the like adapted to be tightened or unscrewed may be successively rotated small portions of a turn without removing the wrench member from the object to be rotated, by slight manipulation of the handle member.

When through using the wrench, the handle member 3 is withdrawn to the dotted line position shown in Fig. 3 and then tilted about its pivotal connection with the member 4 to the position shown in Figs. 3 and 4, providing a compact and efficient wrench.

Though we have shown and described a particular construction, combination and arrangement of parts and portions, we do not wish to be limited to this particular construction, combination and arrangement, but desire to include in the scope of our invention, the construction, combination and arrangement substantially as set forth in the appended claims.

Having thus described our invention, what we claim as new and desire to secure by Letters Patent is:

1. In a wrench structure of the character described, a wrench member provided at one end with a wrench portion and at its opposite end with a plurality of notches, a handle member, and a retainer pivotally connected to said handle and extending into the wrench member, said handle member being adapted to be inserted into said notches for rotating the wrench member, and to be withdrawn therefrom, and adapted, when withdrawn, to be folded against the side of the wrench member.

2. In a wrench structure of the character described, a wrench member provided at one end with a wrench portion and at its opposite end with a plurality of notches, a handle member, and a retainer pivotally connected to said handle and rotatably and slidably mounted in the wrench member at the end thereof provided with said notches, said handle member being adapted to be inserted into said notches, for rotating the wrench member and to be withdrawn therefrom, and adapted, when withdrawn, to be folded against the side of the wrench member.

3. In a wrench structure of the character described, a wrench member provided at its one end with a plurality of notches, a handle member adapted to be inserted in said notches, and provided near its one end with a portion extending at a right angle therefrom and adapted to extend into and

be withdrawn from the end of the wrench member provided with the notches, and a retaining member pivotally connected to the end of the portion extending at a right angle from said handle member for retaining the same in a certain position relative to said wrench member.

4. In a wrench structure of the character described, a wrench member provided at its one end with a plurality of notches, a handle member adapted to be inserted in said notches, and provided near its one end with a portion extending at a right angle therefrom and adapted to extend into and be withdrawn from the end of the wrench member provided with the notches, and a retaining member pivotally connected to the end of the portion extending at a right angle from said handle member for retaining the same in a certain position relative to said wrench member, the length of the portion extending at a right angle from said handle member being such as to permit said handle member to be folded to one side of and adjacent said wrench member.

5. In a wrench structure of the character described, a wrench member provided at one end with a wrench portion and at its opposite end with a plurality of notches, a handle member, and a retainer connecting said handle member to said wrench member, whereby said wrench member is permitted to be inserted into said notches and to be folded to one side of the wrench member when withdrawn from said notches.

6. In a wrench structure of the class described, a wrench member having notches at one end, a handle means adapted to be inserted into said notches for rotating the wrench member, means for retaining said handle means relative to said wrench member, said handle means being foldable to one side of the axis of the wrench member.

7. In a wrench structure of the class described, a tubular wrench member provided at its one end with a plurality of notches, a handle member adapted to be positioned at its one end in said notches and provided at said end with an extended right angle portion extending inwardly into the interior of said tubular wrench member, a guide means at the one end of said wrench member provided with said notches into which the right angle portion of said handle member is adapted to be inserted, and a retaining member pivotally connected to the end of the right angle portion adapted to retain the handle member in certain positions relatively to said wrench member and to permit said handle member to be folded along one side of said wrench member.

8. In a wrench structure of the character described, a tubular wrench member provided at its one end with a polygonally shaped socket portion and at its opposite end with a

plurality of diametrically opposed relatively deep notches, a retaining means in the end thereof provided with said notches, and a handle member, in the form of a rod, adapted 5 to be positioned, with the one end of its rod and also with a portion at a distance from said end, into two of said opposed notches and provided near said end with a rigidly connected right angle portion adapt- 10 ed to extend through said retaining means.

9. In a wrench structure of the character described, a tubular wrench member provided at its one end with a polygonally shaped socket portion and at its opposite end 15 with a plurality of diametrically opposed relatively deep notches, a retaining means in the end thereof provided with said notches, a handle member adapted to be positioned, with its one end and also with a portion at a distance from said end, into two of said opposed notches and provided near said end with a rigidly connected right angle portion adapted to extend through said retaining means, and a retaining member 20 pivotally connected to the end of said right angle portion extending through the retaining means of said wrench member to limit the withdrawal of the handle member from said wrench member and also to permit the folding of said handle member to one side of and adjacent said wrench member.

10. In a wrench structure of the character described, a tubular wrench member provided at its one end with a polygonally shaped socket portion and at its opposite end with a 25 plurality of diametrically opposed relatively deep notches, a retaining means in the end thereof provided with said notches, a handle member adapted to be positioned, with its one end and also with a portion at a distance from said end, into two of said opposed notches and provided near said end with a rigidly connected right angle portion adapted to extend through said retaining means, and a retaining member pivotally connected at the end of said right angle portion adapted to engage the retaining means of said wrench member when said handle member is withdrawn.

11. In a wrench structure of the character described, a tubular wrench member provided at its one end with a polygonally shaped socket portion and at its opposite end with a 30 plurality of notches in its one end, a handle member, in the form of a rod adapted to extend across said end with the notches and engage with its rod portion, notches on opposite sides of the wrench member, and means connecting said handle member with said wrench member but permitting the removal of said handle from said notches.

11. In a wrench structure of the character described, a wrench member provided with a plurality of notches in its one end, a handle member, in the form of a rod adapted to extend across said end with the notches and engage with its rod portion, notches on opposite sides of the wrench member, and means connecting said handle member with said wrench member but permitting the removal of said handle from said notches.

11. In a wrench structure of the character described, a wrench member provided with a plurality of notches in its one end, a handle member, in the form of a rod adapted to extend across said end with the notches and engage with its rod portion, notches on opposite sides of the wrench member, and means connecting said handle member with said wrench member but permitting the removal of said handle from said notches.

In testimony whereof, we have hereunto 60 set our hands at San Diego, California, this 9th day of February, 1925.

GEORGE BROWNING.
PATRICK J. BOHAN.
